Term of patent 7 years

(Cl. D90—20)

Fig. 1

*Fig. 3**Fig. 2**Fig. 4**Fig. 5*Fig. 1 is a perspective view of a tire embodying our new design, it being understood that the full line portion is repeated throughout the circumference of the tire, as shown by means of broken lines;

Fig. 2 is an enlarged fragmentary side elevational view of the full line portion shown in Fig. 1;

Fig. 3 is an enlarged fragmentary plan view of the full line portion shown in Fig. 1;

Fig. 4 is a sectional view taken substantially on the plane indicated by line IV-IV of Fig. 3; and

Fig. 5 is a detailed sectional view taken substantially on the plane indicated by line V-V of Fig. 4.

The dominant features of our design reside in those portions shown in full lines in the drawings.

We claim:

The ornamental design for a tire, substantially as shown and described.
